UNITED STATES PATENT OFFICE.

HENRY B. WILLIAMS, OF ROCHESTER, NEW YORK, ASSIGNOR OF TWO-
THIRDS TO L. A. JEFFREYS, OF SAME PLACE.

PROPELLING APPARATUS FOR VESSELS.

SPECIFICATION forming part of Letters Patent No. 367,125, dated July 26, 1887.

Application filed November 16, 1886. Serial No. 219,066. (No model.)

To all whom it may concern:

Be it known that I, HENRY B. WILLIAMS, of the city of Rochester, in the county of Monroe and State of New York, have invented 5 a certain new and useful Improvement in Propelling Apparatus for Boats; and I do declare that the following is a full, clear, and exact description of the same, reference being had to the drawings accompanying this application.

My improvement relates to propelling apparatus for small steam-yachts, and is also adapted to larger steam craft. It is of that kind where a bracket or frame is hinged at 15 the inner end to rise and fall, and to which is attached a shaft and propeller which rise and fall with the same, the shaft having a universal coupling by which it can receive rotary motion at all angles, as hereinafter described. 20 In the drawings, Figure 1 is a longitudinal section of the rear end of a boat, showing my improvement applied thereto. Fig. 2 is a similar view showing the propeller applied farther forward, or within the length of the boat. Fig. 25 3 is a plan view of the propelling apparatus.

A indicates the frame, which consists of a metallic arm of considerable length, provided with right-angled bearings *a a*, through which runs the shaft *B*, having at its outer end an 30 ordinary propeller, *C*. At the inner end of the frame is an arm, *b*, which stands at an obtuse angle and serves as a stop, striking against a shoulder, *c*, of the boat to limit the fall of the frame. At the inner end are also 35 two side pivots or journals, *e e*, that rest in suitable bearings of the boat and serve as the attachments for the frame and allow it to turn up and down. The bottom *d* of the frame is made thin edged, forming a sort of knife or cutter that will cut through weeds, and the outer 40 end, *f*, is bent slightly upward to inclose the lower edge of the propeller. The inner end of the propeller-shaft *B* has a universal coupling-joint, *g*, which connects it with the main shaft 45 *B'*, so that the propeller can receive rotary motion at whatever angle the frame may run.

E shows the boat having a center space or slot, *h*, on the under side and in the stern-post,

to allow the frame to rise and fall therein, and at the rear of this slot is an enlarged space, *h'*, 50 for the propeller to enter when raised. In Fig. 2 the apparatus is shown attached to the boat some distance in from the rear end, in which case the space *h'* has an enlarged inclined opening, *h''*, at the rear to allow reaction 55 against the water when the propeller is running high.

In Fig. 1 the apparatus is set at the rear end of the boat, so that the propeller acts directly outward. The apparatus is raised or lowered 60 by a cord or chain, *k*, running on a windlass or any other suitable device.

This device is specially applicable to small steam-yachts, and it is designed to lower the propeller and let it hang loose under the boat. 65 It is limited in the down movement by the arm *b* striking against the shoulder *c*. In passing over obstructions the bottom of the frame acts like a runner, and in passing through weeds or other light obstructions the bottom 70 will act as a cutter, so that they can separate to prevent clogging the propeller. It is particularly adapted to inland waters encumbered by weeds. When drawn up, the apparatus strikes into the slot made for its reception like a center-board in its well. 75

Having described my invention, I do not claim simply and broadly a propeller at the rear of the boat capable of being raised and lowered at different heights; but 80

What I claim as new, and desire to secure by Letters Patent, is—

The propelling apparatus described, consisting of the frame constructed with a thin-edged bottom with bearings for the attachment of the 85 propeller-shaft and propeller, with an inclined arm at the inner end forming a stop, and with side pivots by which it is attached to the bottom of the vessel, as set forth.

In witness whereof I have hereunto signed 90 my name in the presence of two subscribing witnesses.

HENRY B. WILLIAMS.

Witnesses:

R. F. OSGOOD,
WM. J. MCPHERSON.
